CLEANING MACHINE

Howard C. Porter, South Bend, Ind., assignor to
 Bendix Home Appliances, Inc., South Bend,
 Ind., a corporation of Delaware

Application January 18, 1941, Serial No. 374,977

3 Claims. (Cl. 285—90)

This invention relates to cleaning machines and, more particularly, to a construction for filling such machines with cleaning liquid.

A primary object of this invention is the provision of a filling device for cleaning machines which is very easily attached and detached and which includes a nozzle directed in substantially the same direction as the hose to which it is attached, so that it can be conveniently used for purposes other than filling the cleaning machine.

Another object of the invention is to provide a cleaning machine having a filler opening and a cooperating nozzle so constructed as to hold the nozzle in place during filling.

Still another object of the invention is to provide a cleaning machine including a cylindrical tub having a filling opening in its side wall and a nozzle arranged to discharge cleaning liquid tangentially into the tub.

Another object is to provide a filling nozzle connected to a supply of temperature-adjustable water, the nozzle leaving an exposed metal portion in good heat conducting contact with the water and readily contacted by the operator's hand, by means of which the temperature of the water entering the tub can be readily determined within necessary limits.

The above and other objects, advantages and novel features of the invention will be apparent from the following description when read in connection with the accompanying drawing, in which:

Figure 1 is a perspective view of a cleaning machine embodying the invention with parts broken away;

Figure 2 is an enlarged vertical section through the filler opening with the nozzle in place; and

Figure 3 is a section on the line 3—3 of Figure 2.

The illustrated cleaning machine comprises a cylindrical tub 10 supported on a base 12 with its axis horizontal and having an opening in one end closed by a door 14 for the introduction of material to be cleaned. Within the tub 10 a perforated drum 16 is mounted for rotation on a horizontal axis and is adapted to be driven by a motor or the like mounted in the base 12.

For filling the tub with cleaning liquid such as water there is provided an opening in the top of the tub defined by an upturned flange 18 adapted to receive a grommet 20 of yielding material such as rubber. As shown, the grommet has a flanged portion 22 adapted to fit over the flange 18 and an enlarged inner portion 24 extending

through the flange 18 and engaging the inner side of the tub to hold the grommet in place.

In its central portion the grommet is provided with an elongated slot 25, as best seen in Figure 5, whose long sides are defined by arcuately curved wall portions 26, the cross section of the grommet in a plane normal to the side wall of the slot having the shape of the cross section of an anchor ring. The wall portions preferably extend inwardly through an arc of substantially 90° from the throat of the slot and may, if desired, be carried outwardly past the throat to form a flaring mouth.

The tub is adapted to be filled by a city water supply or the like, indicated generally at 28, through a flexible hose 30. At its outer end the hose 30 carries a nozzle 32 formed of a metal conduit bent through substantially 90°. At its discharge end the conduit is flattened as at 34 to conform in section to the shape of the slot in the grommet and is bent through an arc of substantially 90°. To fill the tub the nozzle portion 34 is inserted through the slot in the grommet 20 and is swung around to the position shown in Figure 2 with the curved portion 34 lying against one of the like arcuate walls 6 and discharging substantially tangentially of the tub. In this position the nozzle portion 34 serves to lock the nozzle in the grommet, so that it will remain in place without the necessity of any external holding means during filling of the tub. It also will be noted that the nozzle discharges tangentially between the tub and the drum so as to fill the tub rapidly with a minimum of splashing.

While one embodiment of the invention has been shown and described in detail, it will be understood that this is illustrative only and is not intended as a definition of the scope of the invention, reference being had for this purpose to the appended claims.

What is claimed is:

1. In combination, a fluid receiving tank having an opening through its wall, a rubber grommet secured in the opening, said grommet having a slot-shaped opening therethrough, one cross section of the grommet having the interior shape of the interior of an anchor ring, and a removable nozzle fitting said grommet opening and having a portion lying against the inner part of the grommet at one side of the grommet opening to prevent the removal of the nozzle by a force applied in line with the opening through the grommet, said nozzle being readily removable from the grommet by rotation on an axis lying within the grommet and parallel with

the slot-shaped opening therein and parallel with the tank wall in which the grommet is secured.

2. In combination, a fluid receiving tank having an opening therein, a flexible grommet fitted into said opening and having a portion overlying and underlying the tank wall about the opening therein, said grommet having a passage therethrough elongated in the plane of the tank wall and extending from without to within the tank, the part of said grommet lying on one side of the passage therethrough being substantially circular in the cross section, and a nozzle having an elongated cross section of a size snugly to fit the passage through the grommet and having a portion within the tank engaging the inner curved surface of the substantially circular part of the grommet to prevent the removal of the nozzle by a force in line with the passage through the grommet but permitting the re-

moval of the nozzle by rotating it about the center of said circular part of said grommet.

3. A flexible grommet having an anchor-ring shaped cross section, a nozzle of a size to fit the opening through the grommet, the discharge end of the nozzle being curved to conform to the inner face of the grommet and discharging at substantially right angles to the opening through the grommet, the portion of the nozzle external 10 of the grommet extending substantially parallel to the line of discharge from the nozzle but in the opposite direction, and a flexible hose attached to the external portion of the nozzle for assisting in preventing the nozzle from accidentally rotating in the grommet to a position 15 in which the discharge end of the nozzle falls in alignment with the opening through the grommet.
